W. J. SUMMERBELL
ROOFING TRUSS STRUCTURE

Filed May 29, 1922

UNITED STATES PATENT OFFICE.

WILLIAM J. SUMMERBELL, OF ALHAMBRA, CALIFORNIA.

ROOFING-TRUSS STRUCTURE.

Application filed May 29, 1922. Serial No. 564,402.

To all whom it may concern:

Be it known that I, WILLIAM J. SUMMERBELL, a citizen of the United States, and a resident of Alhambra, in the county of Los Angeles and State of California, have invented certain new and useful Improvements in Roofing-Truss Structures; and I do hereby declare that the following is a full, clear, and exact description thereof, reference being had to the accompanying drawings, and to the characters of reference marked thereon, which form a part of this specification.

This invention relates to improvements in end truss constructions for supporting trusses from the wall of a building or like structure, such, for instance, as a truss that is designed to support the roof of a building. My improvements may be applied to that type of truss shown in my prior United States Patent Number 1,392,882 dated October 4, 1921, but is capable of adaptation to specifically different trusses without departure from the principle of the present invention.

Among the objects of the invention is to provide an end truss construction in which is embodied a laminated top chord so arranged with respect to the bottom chord and the connection between said chords that the forces at the end of the truss are concentric or in equilibrium.

A further object of the invention is to provide an end truss construction wherein the laminations of the top chord take the load through end grain thrust of the chord laminations against a fixed part of the bottom chord, so as to thereby strengthen the truss end.

Another object of the invention is to bring the roof joists or purlins lower relatively to the bottom, thus saving in surrounding brickwork of the wall enclosure.

A further object of the invention is to provide an improved support between the truss end and the wall, which can be anchored in the wall while the wall is being built, and to which the truss can be bolted or otherwise fastened to form a strong joint between the truss end wall.

The invention consists in the combination and arrangement of the elements shown in the drawings and described in the specification, and is pointed out in the appended claims.

As shown in the drawings:

Figure 1 is a side elevation of a truss end

embodying my invention, showing the manner of its support on the wall and showing the sheathing in section.

Figure 2 is a plan view of the bottom chord and its top chord supporting stirrup and the bearing plate.

Figure 3 is a section on line 3-3 of Figure 1.

Figure 4 is a section on the line 4-4 of Figure 1.

Figure 5 is a section on the line 5-5 of Figure 1.

Figure 6 is a fragmentary perspective view showing the ends of the upper and lower chords.

As shown in the drawings, 10 designates one of the vertical enclosing walls of a building and 11 designates as a whole a roof truss, of which there are a number arranged side by side to support the roof structure. Each truss comprises a top laminated chord 12 and a bottom chord 13, said chords being connected by web members 14 of any suitable type, one being herein shown. The bottom chord, as shown, comprises two or more members 15, 15 spaced to receive the lower ends of the web members 14 and to which said web members are bolted. The bottom chord also embraces at its ends fillers 16 which extend to the ends of said bottom chord and preferably are made deeper than the side members of said bottom chord so as to extend at their top edge above the upper edges of the bottom chord members.

The top chord comprises a plurality of laminated members 17 which are constructed in the same general manner as the top chord of the truss shown in my said prior patent. The laminations of the top chord are made in two separated or spaced series to provide a longitudinal recess 11' in each top chord to receive upper ends of the web members 14. The lower strata of laminations are made wider than the upper strata to provide ledges 20. 18 designates the roof sheathing and 19 designates purlins by which the sheathing is supported from the top chord. As shown in Figure 4, said purlins are notched to take over the top chords and bear at their lower edges on ledges 20 made unitary parts of and extending laterally from the top chord, and also bear against the upper faces of the top chord at the recessed portions thereof.

21 designates a base plate which is built into the wall structure and is anchored there-

to, as by means of an anchor bolt 22. The bottom chord lies on and is fastened to the plates, as by means of lag screws 23 or other suitable fastening devices that extend through the plates and into the bottom chord.

The members 15 of the bottom chord terminate at their outer ends in a diagonal plane, indicated at 25, short of the outer 10 end of the fillers 16. The laminations of the top chord fit near their outer ends on the diagonal ends of the members 15 of the bottom chord, and the filler 16 extends through the slot or recess 11' in the laminated top 15 chord, as shown in Figure 2. Said top and bottom chords are secured together and to a metal stirrup 26 by a bolt or bolts 27. Said stirrup is of U-shape formation. The side members 28, 28 of said stirrup lie horizontally along the sides of the bottom chord and are secured thereto, as by means of the through bolts 29. The closed member 30 of said stirrup extends around the end of the filler 16. The laminations of the top chord 25 bear at their ends, with an end grain thrust, against the closed portion 30 of the stirrup 26 and the said top and bottom chords are rigidly connected to each other and to the strap by means of one or more through bolts 30 27. The lower strata of the laminations of the upper chord are cut to the same width as the upper strata adjacent the end so that the entire end of the upper chord may pass into the stirrup as shown in Figure 6.

An advantage of the construction described resides in the bringing of the ends of the laminations of the top chord with an end grain thrust against the closed portion 30 of the stirrup 26, so as to thereby bring 35 the force or stress of the top chord against the anchor stirrup in a position most favorable for utilizing the full strength of the top chord laminations. Moreover, the construction described, wherein the stirrup lies 40 along the bottom chord and is rigidly fixed thereto, provides an exceedingly rigid connection between the top and bottom chords of the truss through the said stirrup and the end grain thrust of the laminations of 45 the top chord therewith. With the construction thus shown the forces are concentric or balanced at the part of the juncture of the top and bottom chords where the larger part of the material is assembled, or at about the 50 point represented by the bolt 27.

Another advantage of the construction shown is that the bearing plate 21 may be set into the wall 10 during the erection of said wall and in such position that the truss may 55 be readily fastened thereto, so as to produce a rigid and durable connection between the truss and the wall structure.

A further advantage of the manner of assembling the stirrup with the truss elements, 60 wherein the stirrup assumes a horizontal

and parallel relation to the bottom chord, is that the entire truss end and the sheathing supported by the truss may be considerably lowered on the wall 10 and thereby effect material saving of masonry in the wall 70 above the point of anchorage of the truss in the wall.

I claim as my invention:

1. In a truss, the combination with top and bottom chords the top chord comprising a 75 plurality of superposed laminated members and a metal stirrup embracing and fastened to the truss end, with the extreme end of the top chord throughout its depth fitted in end grain abutting contact with said stirrup.

2. In a truss, the combination with top and bottom chords, with the end of the bottom chord the top chord comprising a plurality of superposed laminated members, obliquely engaging the top chord inside the 85 supporting point of the latter, and a horizontal U-shaped metal stirrup embracing and fastened to the truss end, with the extreme end of the top chord throughout its depth fitted in end grain abutting contact 90 with the closed point of said stirrup.

3. In a truss, the combination with top and bottom chords, said top chords embracing laminated members and a metal stirrup embracing and fastened to the truss end, the 95 entire ends of the laminations of the top chord being fitted in direct end grain contact with said stirrup.

4. In a truss, the combination with top and bottom chords, the top chord comprising a plurality of superposed laminated members, being bowed and longitudinally slotted, and the end of the bottom chord obliquely abutting the top chord inside the 100 supporting point of the latter, and a metal stirrup embracing and fastened to the truss end, with the extreme end of the top chord fitted throughout its depth in end grain abutting contact with said stirrup, the bottom chord being provided with an intermediate extension which projects into the slot of the top chord at the end of the truss.

5. In combination with the top and bottom chords of a truss connected by web members, the bottom chord having a vertical, longitudinal slot, a filler member in said slot extending endwise and at its top beyond the bottom chord and the bottom chord terminating inwardly therebeyond obliquely to the plane of the chord, the upper chord embracing a plurality of laminations fitted on the oblique face of the lower chord and all bearing at their ends in end grain abutting contact with a part rigid with the lower chord, said top chord being longitudinally slotted to receive the end of said filler member.

6. In combination with the top and bottom chords of a truss connected by web members, the top chord comprising a plu- 130

rality of superposed laminated members, said bottom chord being terminated obliquely to the plane of said bottom chord, a U-shaped stirrup fitted to the bottom 5 chord and extending at its closed portion beyond the bottom chord, and the top chord bearing near its end against the oblique portion of the bottom chord and directly fitting throughout its end with an end grain 10 thrust against the closed part of said stirrup.

7. In combination with the top and bottom chords of a truss connected by web members, the bottom chord having a vertical, 15 longitudinal slot, a filler member in said slot, said filler member extending endwise and at its top beyond the bottom chord and said bottom chord terminating obliquely

to the plane of said bottom chord, a U-shaped stirrup fixed to the bottom chord 20 with the closed portion endwise beyond said bottom chord, the top chord comprising a series of laminations which fit near the end of the truss on the oblique portion of the bottom chord, with the laminations thereof 25 all bearing directly with end grain thrust against the closed part of said stirrup, and a bolt extending through the top and bottom chords and through the side members of the stirrup for fixing said parts together. 30

In witness whereof I claim the foregoing as my invention, I hereunto append my signature this 12 day of May, 1922.

WILLIAM J. SUMMERBELL.
